UNITED STATES PATENT OFFICE.

DORA RENCHER, OF SALT LAKE CITY, UTAH, ASSIGNOR OF ONE-FOURTH
TO ABBIE H. COWLEY, OF SAME PLACE.

GARMENT-FITTER.

SPECIFICATION forming part of Letters Patent No. 678,515, dated July 16, 1901.

Application filed March 14, 1900. Serial No. 8,687. (No model.)

To all whom it may concern:

Be it known that I, DORA RENCHER, a citizen of the United States of America, and a resident of Salt Lake City, Salt Lake county, 5 State of Utah, have invented a certain new and useful Dress-Fitter, of which the following is a specification.

In the drawing I have shown a plan view of the garment-fitter.

10 Reference now being had to the details of the drawing by letter, A and A' and B and B' designate the waist-straps, made of any suitable material. The ends of the straps A' and B are pivoted together at a. The bands O and O' surround the pairs of straps and have 15 detents O², designed to normally hold the straps in adjusted relations. By pushing the bands so that the detents will rest in the apertures P the straps may be easily adjusted.

20 The various straps of the fitter are held together and allowed to slide longitudinally through the bands P'. The back straps C, front bust-straps D, and connecting-straps E, F, and G are similarly constructed to be 25 adjustable. To the upper end of strap G are pivoted loops K, each holding a curved open-ended tube K', and passing through each tube is a rod M, about which is tightly coiled a fine wire m, which is provided to offer a large 30 amount of frictional surface to the inner surfaces of said tubes M, and, if desired, a set-screw (not shown) may be employed at each loop to hold the rods M in adjusted positions.

The upper ends of said rods M are pivotally 35 connected to the straps H, and one of said rods is extended beyond its pivotal end and has an eye M', designed to engage a lug N, while an eye Q at the end of a curved coiled-wire-covered rod R (which latter is pivoted 40 to the end of a strap H) is designed to engage a lug H', which pivotally holds the strap H² to the coiled-wire-covered rod R'. Said rod R' passes through a curved open-ended tube R², as does also the rod R, which is also

covered with a closely-coiled wire. Said tubes 45 R² may be held in the loops by means of set-screws. The straps R³ are held to the straps C and D by means of pivots, as shown.

In adjusting the fitter the apparatus is applied to one half of the body first, the eyes 50 M' and Q being caught over the lugs N and H', respectively. Then the rods M are run out to determine the size of the arm-opening and the rods R and R' to determine the size of one half of the circumference of the neck, 55 and said rods may be held in adjusted positions by means of set-screws. Afterward the fitter may be applied to the other half of the body and the measurements compared.

What I claim is—

60 A dress-fitter, consisting of the adjustable waist, bust and back straps pivoted together as described, the adjustable under-arm straps and adjustable connections between the latter and said bust and back straps, the loops 65 having pivotal connection with the upper ends of the bust and back straps, combined with the curved open-ended tubes mounted in said loops, the adjustable shoulder-straps, the curved neck and arm rods, and coiled 70 wire about said rods, the latter having pivotal connection with the outer ends of said shoulder-straps, and passing through said tubes, the lugs at the outer ends of one pair of shoulder-straps and the eyes formed in the 75 projecting flat ends of the rods at the ends of the other pair of shoulder-straps, whereby as said eyes are brought into engagement with the lugs, the two curved neck-rods are brought together, forming substantially a semicircle, 80 as set forth.

In witness whereof I have hereunto set my hand in the presence of two witnesses.

DORA RENCHER.
